UNITED STATES PATENT OFFICE.

ISAAC J. BAXTER, OF PEEKSKILL, NEW YORK.

DESIGN FOR A HEATING-STOVE.

Specification forming part of Design No. 6,340, dated January 14, 1873.

To all whom it may concern:

Be it known that I, ISAAC J. BAXTER, of Peekskill, in the county of Westchester and State of New York, have invented a new and original Design for a Stove, of which the following is a specification:

For the portion B of the stove between the fire-pot A and the ring C, which is to be open for illuminators, I arrange lancet windows in pairs, inclosed in a bead or rib, b, and having points d projecting inward from the window-frame; and on the surface of this part of the stove I arrange the raised figures represented at e. Above the open portion of the stove above described I have an overhanging ring, C, with points E' projecting downward between the pairs of windows. On the cylinder, above

the ring C and below the cap E, I have the continuous vertical ribs g alternating with the broken ribs and dots h.

What I claim as my invention is—

1. The design for the part B of the stove between the fire-pot A and the ring C, substantially as shown.

2. The design for the ring C, substantially as shown.

3. The design for the cylinder D between the ring C and the top E, substantially as shown.

ISAAC J. BAXTER.
